UNITED STATES PATENT OFFICE.

DANIEL RHEINAUER, OF NEW YORK, N. Y.

SWEATER.

1,158,290.

Specification of Letters Patent. Patented Oct. 26, 1915.

Application filed July 2, 1914. Serial No. 848,557.

To all whom it may concern:

Be it known that I, DANIEL RHEINAUER, a citizen of the United States, and a resident of New York, in the borough of Manhattan, county and State of New York, have invented certain new and useful Improvements in Sweaters, of which the following is a specification.

This invention relates to sweaters and has for its object to provide an improved sweater having a detachable collar so that the sweater may be used conveniently in rough weather as also in mild weather, and for this purpose the invention is shown in the accompanying drawing and will be more fully described hereinafter and finally pointed out in the claim.

In the accompanying drawing, Figure 1 is a front view of a sweater having my improvement thereon. Fig. 2 is a front view of a collar therefor, Fig. 3 is a rear view of the same collar, Fig. 4 is a partial view of a sweater with the collar in inward position, Fig. 5 is a partial view of a sweater with the collar in outward position, Fig. 6 is a partial view of a sweater with the collar in upward position in the form of a choker, Fig. 7 is a section taken on line 7—7 of Fig. 1, Fig. 8 is a section taken on line 8—8 of Fig. 4, Fig. 9 is a section taken on line 9—9 of Fig. 5, and Fig. 10 is a section taken on line 10—10 of Fig. 6.

Similar characters of reference indicate corresponding parts throughout the various figures of the drawing.

In the form of embodiment illustrated in the drawing, the knit garment comprises a sweater body provided with pockets 11 at the front thereof, sleeves 12 at the sides thereof and the usual marginal band 13 at the meeting edges thereof, which band extends around the neck opening, the latter being of V-shape. The band 13 is provided on its inner face along the V-shaped neck opening adjacent to the edge thereof with a tape 15. This tape extending from the point 16 at the end of the V-shape upwardly and rearwardly and downwardly to said point is indicated in dotted lines in Fig. 1. This tape is provided with a series of fastener members, the sockets or eyelets 18 thereof being open on the inner face of the tape.

The collar 21 has a concave inner edge and is provided along said concave inner edge on its outer face with a tape 20 which carries a series of fastening members 19,

preferably of the stud form, adapted to engage the socket members 18 of the body. The collar is preferably constructed in three sections, two triangular end sections 23 and 24 and an intermediate central section 22 having edges which are joined with the inner ends of the end sections on lines 25 and 26 as indicated in Fig. 3. The end section 24 is provided on its exterior near its center with buttons 31 and 32 and the end section 23 is provided at its edge with loops 29 and 30 adapted to engage said buttons.

In the form illustrated in Fig. 4 the collar 21 serves as an inner cape. In this case the edge carrying the fasteners 19 is the upper edge of the collar and said fasteners are made to engage the fasteners 18 along the neck opening of the body. In this construction the collar is completely covered by the body and the garment presents the appearance of a coat sweater instead of an ordinary turnover sweater.

In Fig. 5 the collar is shown in a different position. It has been removed from the position shown in Fig. 4, and completely detached therefrom, and then reversed endwise placed into the position shown in Fig. 5, and fastened by the interengagement of the members 19 and 18.

A section taken on line 9—9 of Fig. 5 is clearly shown in Fig. 9, in which the fastening members 18 and 19 engage each other, and the collar 21 extends rearwardly over the sweater 40.

In Fig. 6 another position of the collar is shown, namely that in raised position, to be specially used in the case of wintry weather. This is also clearly shown in Fig. 10 by the section taken on line 10—10 of Fig. 6, in which is shown the engagement of the members 18 and 19 and the collar 21 extending in upward position.

Having thus described my invention, I claim as new and desire to secure by Letters Patent:—

A knit garment comprising a body having a V-shaped neck opening, a knit band along said opening, said band being provided on its inner face adjacent to said opening with a tape carrying a series of fastener members, a detachable endwise reversible collar having a concave inner edge and provided along said concave inner edge with a tape carrying a series of complementary fastener members adapted to engage said fastener members of the body in

either endwise position of said collar; said detachable collar being adapted when disposed so that its fastener members are along its upper edge to form an inner cape in-
5 closed within said body, the garment then having the appearance of a coat sweater or when reversed endwise and disposed with its fastener members along its lower edge
10 as a standing or turnover collar, and fastening devices for the ends of the collar adapting it to serve as a choker in standing posi-

tion comprising buttons disposed centrally of one end member on the outer face thereof and loops at the edge of the other end member adapted to engage said buttons

15

In testimony, that I claim the foregoing as my invention, I have signed my name in presence of two subscribing witnesses.

DANIEL RHEINAUER.
